INTERNAL COMBUSTION ENGINE

Knut Jonas Elias Hesselman, Saltsjö-Stockarängen, and Torbjörn Viktor Dillström, Stockholm, Sweden, assignors to Hesselman Motor Corporation Ltd., London, England, a corporation of Great Britain

Original application October 6, 1934, Serial No. 747,134. Divided and this application December 21, 1935, Serial No. 55,572. In Sweden March 10, 1934

4 Claims. (CL. 123—32)

This application is a division of our co-pending application Serial No. 747,134 filed October 6, 1934.

The present invention relates to internal combustion engines of the type in which finely divided or atomized liquid fuel is injected into the combustion chamber of the engine and mixed with air therein to form a combustible fuel charge. More particularly the invention relates to engines of the type in which, during normal operation, a complete or substantially complete charge is formed in the engine cylinder prior to the time of ignition and is ignited, in normal operation of the engine, by spark or a like kind of ignition. Stated in another way, the invention relates to engines operating substantially in accordance with the so-called Otto cycle, rather than in accordance with the Diesel cycle which contemplates injection of fuel into an air charge which has been compressed to such high pressure that the resulting temperature of the air causes ignition of the fuel due to the heat of compression upon contact of fuel with the compressed air charge. Still more particularly the invention relates to engines of the above described Otto cycle type adapted to operate at relatively high speeds.

In one of its aspects, the present invention may be considered as an improvement, with respect to certain kinds of engines, upon the construction of engines of the Hesselman type as disclosed in U. S. Patent No. 1,835,490.

Amongst the principal objects of the invention are; to provide an improved construction resulting in improved efficiency of operation and better fuel economy in engines of the kind under consideration; to provide an improved engine construction whereby engines of the kind under consideration may be operated at high speed with high efficiency; to provide improved engine construction for engines of the character under consideration which permits the satisfactory employment of higher compression ratios than it has been possible to employ heretofore, with consequent increase in power output for a given size of engine, and to provide improved apparatus whereby ordinary gasoline engines may be converted easily and cheaply for operation as injection engines using relatively heavy and non-volatile oil for fuel.

Other and more detailed objects of the invention, together with the manner in which the several objects are attained and the advantages to be derived from the use of the invention, will appear more fully in conjunction with the en-

suing description of several embodiments of apparatus for carrying the invention into effect, which embodiments are illustrated in the accompanying drawings forming a part of this specification.

In the drawings:

Fig. 1 is a longitudinal section through the cylinder of an engine embodying the invention;

Fig. 2 is a view taken on the line 2—2 of Fig. 1;

Fig. 3 is a section similar to Fig. 1 showing another application of the invention;

Fig. 4 is a view taken on the line 4—4 of Fig. 3;

Fig. 5 is a section showing still another application of the invention; and

Fig. 6 is a view taken on the line 6—6 of Fig. 5.

Referring now more particularly to Figs. 1 and 2, the engine illustrated is of the overhead valve type and comprises the cylinder block 10 having the separable inserted cylinder liner 12 and the cylinder head 14. Head 14 is detachable from the cylinder and is retained in place by the usual cylinder head studs (not shown). Piston 16 is provided with a head or crown portion 18 from which extends upwardly the peripheral collar portion 20, the construction providing what may be termed a cup at the upper end of the piston. The piston is connected to the usual connecting rod 22 by means of the wrist pin 24. The piston is provided with the usual compression and oil control piston rings 26, 28 and for reasons which will hereinafter appear one or more of these rings is advantageously seated in the collar portion 20 of the piston, as shown in Fig. 1. In the embodiment illustrated, the cylinder head 14 has a generally flat under surface forming the top wall of the combustion or compression chamber 30, the wall surface of which is substantially entirely defined by the under side of the head and the cup portion of the piston when the piston is at the upper end of its stroke. When the piston is at top dead center position, the top of the collar portion of the piston preferably extends to, or almost to, the top edge of the cylinder wall so as to substantially cover the lubricated side wall surface of the cylinder. Head 14 carries the inlet valve 32 and exhaust valve 34 which valves are closed in the usual manner by springs 36 and are opened downwardly toward the combustion chamber by rocker arms 38 actuated by push rods 40, the rods 40 in turn being actuated by cams on the usual cam shaft (not shown).

Air is admitted to the combustion chamber by way of inlet valve 32 through the inlet passage 42 formed in the head and adapted to be con-

nected to the usual air induction pipe (not shown).

In the embodiment illustrated in Fig. 1, the seat for the inlet valve is located in a recess 44 in the under side of the cylinder head. The portion 46 of the wall of this recess is cylindrical and merges into the inclined portion 48 to provide for tangential admission of air to the cylinder when the inlet valve is opened, as indicated by the arrows in Fig. 2.

The exhaust passage 50 leads from the exhaust valve 34 to the side of the cylinder head in the usual manner for connection to the exhaust manifold (not shown).

A spark plug 58 is mounted in the head 14 so as to project downwardly into the combustion chamber from the under side of the head 14. In an engine of the kind illustrated in Fig. 1, that is, with relatively small bore, the plug is advantageously located near the periphery of the combustion chamber. Plug 58 is preferably of the usual high tension jump spark type to which current is supplied at timed intervals by the usual battery or magneto ignition system.

An injection nozzle 52 is mounted so that its tip 56 is located in the upper portion of the combustion chamber 30. Advantageously the injection nozzle is mounted in head 14 although it will be evident to those skilled in the art that the line of partition between the cylinder block and the head may be inclined so that the injection nozzle may be mounted in the block in a position corresponding to the position shown in Fig. 1. The tip of the injection nozzle is advantageously located, in an engine of the kind described, near the periphery of the combustion chamber at the side thereof opposite the spark plug.

While the number and specific form of the jet or jets of atomized fuel injected into the combustion chamber may vary within the scope of the invention, we have found it preferable in engines having relatively small or moderate size cylinder bores to inject the fuel in two diverging jets which are projected transversely of the cylinder and downwardly from the nozzle at an angle to the axis of the cylinder. The center lines of the jets, when injection is as above described, are shown at 60 and 62.

Instead of jets of the kind illustrated, the charge may be injected in the form of a flat fan shaped jet of wide lateral dispersion directed angularly downwardly from the injection nozzle but, for practical operating reasons, we prefer to employ one or more jets projected from circular orifices which are less likely to clog than is a slit orifice, one dimension of which must be exceedingly small.

In order to prevent interference between the collar portion of the piston on the one hand and the spark plug, injection nozzle and valves on the other hand, the collar portion of the piston, in small engines, may be recessed at 64, 65 and 66 as indicated in Fig. 1. It will be observed, however, that even with such minor recesses, the collar portion of the piston is continuous for the greater part of its height above the bottom of the piston cup and for the purposes of the present invention may be considered as continuous.

With the above described construction in mind, we will now consider the more important requirements for best attaining the objects of the present invention and the manner in which the above described construction meets such requirements.

In an engine of the character under consideration, the compression or combustion chamber is located substantially entirely within the engine cylinder and, with such an arrangement, it is highly desirable when atomized and relatively non-volatile liquid fuel is injected that none of the fuel reaches the cylinder wall. In this connection, it is to be pointed out that with an engine of the kind under consideration, a serious problem arises which is not present in engines of comparable size operating on the Diesel cycle. As previously pointed out, in the kind of engine we are considering, fuel is injected and the charge is formed prior to the time of ignition. When this is done, the fuel which is injected at the commencement of the injection period is projected across the cylinder and during the period between the commencement of injection and the time of ignition, which time is usually somewhat after the termination of the injection period, the cylinder contains a charge of atomized oil being mixed with the air to form the proper combustible charge for firing at the proper time. During this period, it is highly important to prevent exposure of the lubricated cylinder wall surface, or as much thereof as possible, to contact with the fuel charge. The cylinder walls are relatively cool, being ordinarily water jacketed or specially cooled by air or other media and contact of the fuel with cool and lubricated cylinder wall surface causes adherence of fuel to the cylinder wall surface with consequent loss of fuel for combustion purposes and also serious dilution of the lubricating oil.

In the form of engine construction according to the present invention, the difficulty of forming an atomized charge prior to ignition is overcome by protecting the cylinder wall with the collar portion of the piston as the latter approaches the end of the compression stroke and by directing the fuel charge substantially entirely into the cupped portion of the piston. In a typical engine of the kind under consideration, injection of fuel may commence in the neighborhood of 60° ahead of top dead center although in engines operating at relatively low speeds injection may commence even later in the cycle. With a piston of the kind described arranged so that the top of the collar portion of the piston extends substantially to the top of the combustion chamber at top dead center, only a relatively small portion of the cylinder side wall surface is exposed at the time injection commences. It takes an appreciable amount of time for the fuel first injected to travel across the cylinder and by the time this travel has taken place the continued upward movement of the piston places the collar portion in a position such that the cylinder wall is further covered and protected from impingement there against of the injected fuel. Stated in another way, the collar portion of the piston is in the zone of fuel injection at the time injection takes place during the latter part of the compression stroke.

In order to secure the most satisfactory performance of engines of the character described, particularly at part load when the amount of fuel injected is relatively small, it is desirable to assist atomization by some degree of heating of the oil prior to ignition, even to the extent of partial vaporization thereof. The piston is at higher temperature than the cylinder and, by injecting fuel into the cupped portion of the piston, the formation of a readily ignitable fuel charge is materially aided by the heat of the piston.

In operation, the air charge, which is drawn into

the cylinder through the inlet passage 42 during the suction stroke of the piston is, in the embodiment illustrated, given a rotary motion within the cylinder due to the tangential admission of the air along the ramp 48 at one side of the inlet valve 32, and this rotary movement continues during the compression stroke of the engine.

In the preferred embodiment of the invention, we make use of means for imparting tangential admission of the air so as to secure a relatively high speed of whirling movement of the air in the cylinder during the suction and compression strokes for reasons which will hereinafter more fully appear but, as will further be explained, special means for providing tangential admission may not be essential to the operation of all engines within the scope of the invention.

In order to avoid fouling of the spark plug as well as to assist in forming a readily ignitable mixture prior to ignition, the main body of the fuel charge is preferably injected into the cylinder in a direction other than directly at the spark plug and, in the embodiment illustrated, this is accomplished by the downward and lateral projection of the jets as indicated by lines 60, 62. Naturally, there will be some dispersion of fuel from the center of any jet or jets projected into the chamber but such dispersion of the fuel is such that penetration of fuel particles from the outer portions of the jet or jets, which may be directly toward the plug, is insufficient to cause amounts of fuel sufficient to result in fouling, to strike the plug.

In this connection, the downwardly projecting position of the plug from the head into the combustion chamber is of materially practical importance since such unburned liquid fuel as may strike the plug and remain thereon will drain to the lower end of the plug and not collect in quantities on the insulated portions of the plug where such collection would result in short circuiting of the plug and consequent failure of proper action. Moreover the exposed position of the projecting inner end of the plug leaves this portion in a position where it is swept by movement of the air charge within the cylinder during the suction and compression strokes, and such movement of the charge not only serves to assist in cooling the plug so as to keep it below a temperature causing pre-ignition, but also apparently assists in keeping the plug free from accumulations of oil thereon.

As previously stated, we prefer to provide special means for insuring whirling movement of air in the cylinder during the suction and compression strokes, which movement will continue to the end of the compression stroke. Such movement we find to be advantageous when fuel is injected in the manner illustrated in Figs. 1 and 2 since the movement of the air in the general direction indicated by the arrows in Fig. 2 insures fuel from the jet projected along the line 62 being carried to the plug so that an ignitable mixture is in the vicinity of the plug at the time of ignition. Due to the upward movement of the piston during the injection period, which movement ordinarily continues beyond the time of ignition since ignition is usually ahead of top dead center, there is some upward movement of the air in the combustion chamber and this aids in bringing fuel from this downwardly directed jet to the vicinity of the electrodes at the time of ignition. The fuel injected along the line 60, which is projected in a direction generally against the movement of the air, tends to be deflected still further downwardly by the moving air.

While we have found that a regularly defined rotary motion of the air in the cylinder induced by special means for tangential admission is, in most instances, a very desirable factor, there are other considerations which must be taken into account in this connection with respect to different specific engine designs. As is well known, high volumetric efficiency is highly desirable. That is, it is highly desirable to be able to introduce into a cylinder of given size as great a weight of air as possible in order to burn the maximum amount of fuel per charge and thus secure the maximum amount of power from a cylinder of given size. Extremely high rates of air rotation obtained by special tangential air admission means are ordinarily accompanied by some loss in volumetric efficiency due to the resistance to flow or restricted area of inlet opening accompanying the use of such means. We have discovered that with an overhead valve engine of the kind illustrated, the offset position of the inlet valve with respect to the axis of the cylinder, coupled with the usual form of air inlet passage, which extends laterally to one side of the valve, may produce lateral movement of the air in the cylinder as it is admitted thereto, in a manner such that a certain amount of what may be termed generally whirling movement of the air in the cylinder results. Such construction gives the minimum in the way of resistance tending to reduce volumetric efficiency and, in certain kinds of engines, it may be possible to get sufficient movement of the charge within the cylinder to accomplish the purposes of the invention without resorting to special means for effecting tangential admission.

In connection with the factor of air movement within the cylinder, it is to be noted that the continuous collar type of piston presents a substantially smooth and symmetrical surface giving minimum resistance to any movement of the charge within the cylinder.

When it is desired to make use of relatively high speed air rotation and tangential air admission means is employed in order to insure this character of air rotation, the smoothly symmetrical form of chamber resulting from the use of the continuous collar piston is of assistance since there is with this form of chamber minimum loss in speed of air rotation between the entering speed and the speed existing at the end of the compression stroke. Consequently, in order to obtain a given speed of air rotation toward the end of the compression stroke, that is, during the injection period, minimum air speed above this given speed is required for the air entering the cylinder and the air admission means can therefore be constructed so as to produce the minimum pressure drop.

While the present construction permits the compression ratio to be increased as compared with the compression ratios heretofore found to be feasible, it is to be understood that the increased compression ratios that may be employed in accordance with the present invention are substantially lower than the compression ratios employed for Diesel engines, and that the engine is, insofar as compression classification is concerned, to be considered as a low compression rather than a high compression engine. The range of compression ratios employed in engines of the kind with which the present invention is concerned is of an order such that the engines are not subjected to the severe mechanical stresses characteristic of Diesel engines and such engines may therefore have substantially the same ratio of

weight per horsepower as gasoline engines constructed for the same character of service.

In an engine of the character under discussion ignition is primarily effected by the spark produced at the plug, but it is not intended that the invention be limited to engines where ignition occurs at all times and under all conditions of operation by spark alone. In an engine such as that illustrated, the amount of heat generated under continued full load or overload operation conditions may produce ignition at the end of the compression stroke, but ignition of this character and under such conditions is not productive of the same undesirable character of engine operation as that which is produced by preignition, due to highly overheated and improperly cooled engine parts.

One of the substantial advantages of the present invention is that the apparatus required for carrying the invention into effect readily permits the conversion of existing gasoline engines to engines of the injection type. As previously noted, the character of compression characteristics are such that the pressures generated during the compression and working strokes do not require heavier engine construction than is ordinarily employed for gasoline engines of the same duty, and therefore the conversion of such engines does not require alteration or rebuilding with respect to the major portion of the engine. With apparatus according to the present invention, the conversion of an existing gasoline engine requires only replacement of the existing head and of the existing pistons, and in some instances of the existing inlet valves.

In Figs. 3 and 4 we have illustrated still another form of head for carrying the invention into effect. In this embodiment the head 14c is generally the same as that illustrated in Fig. 1, and is provided with injection nozzle 52 and spark plug 58 located relative to each other as in the embodiment of Fig. 1. In the present embodiment, however, the inlet valve 32 is seated substantially in the plane of the lower face of the head, and tangential admission of air to the compression chamber 30 is effected by means of an air inlet passage 42a, which may be said to be of generally Venturi form having a throat 42b and a longitudinal axis inclined with respect to the transverse plane of the cylinder and tangential with respect to the longitudinal axis of the cylinder. For some types of engines this specific form of air inlet may be preferable to others, and it will be understood, of course, that this type of inlet may be combined with other specific features of construction shown in other embodiments herein.

Figs. 5 and 6 illustrate a slightly different application of the invention. The cylinder head 14d is in general of the same construction as that shown in Fig. 3, but in this instance the injection nozzle 52 and the spark plug 58 are located adjacent to each other on the same side of the diameter of the cylinder.

In all of the embodiments shown herein, injection of fuel is timed so that a fog of finely atomized fuel is carried by the movement of the air in the cylinder to the vicinity of the electrodes of the plug when the spark occurs. Therefore, the timing of the commencement and ending of injection with respect to the timing of the spark may be somewhat different in the form of apparatus shown in Fig. 5 and in the forms shown in the remaining figures, but the manner in which the timing may be varied will be understood by

those skilled in the art and need not be described herein in detail for an understanding of the present invention.

It will be observed that all of the modifications hereinbefore described have certain features in common which are generally characteristic of the invention. Of these we consider the following to be of major importance. In each case, the combustion chamber is of generally circular form and is also generally symmetrical about the longitudinal axis of the cylinder. It may be said to be in the form of a body of revolution about the axis of the cylinder.

We intend to include in the meaning of the above terms as herein employed combustion chambers which may be slightly irregular, as, for example, in some of the forms of combustion chamber construction shown in U. S. Patent No. 2,028,760 granted January 28, 1936 to T. V. Dillstrom, wherein the piston head is angularly disposed and wherein there is an irregular recess for the inlet valve in the cylinder head. The primary requirement is that the combustion chamber be of what we may term the usual form of overhead valve engines, adapted to facilitate the substantially regular whirling or rotation of the air admitted to the cylinder. In all of the modifications the injection nozzle and plug are carried in the head and project into the main combustion space, preferably in positions where the active ends of these elements are in the path of the rotating air.

By carrying the injection nozzle and plug in the head it is not only possible to make use of the continuous peripherally flanged piston, but it is possible to make use of a wet cylinder liner construction such as that illustrated in Fig. 1, that is, a construction in which the removable liner forms the inner wall of the water jacket as well as the cylinder wall. This desirable feature of construction would be impossible with the injection nozzle and plug, or either, carried in the cylinder side wall. It will also be evident that in each case the plug, being carried in the head, extends vertically downward or is inclined downwardly into the combustion chamber from a position generally above the combustion chamber. This positioning of the plug is advantageous in that it facilitates drainage from the plug of any unatomized oil that may adhere thereto due to injection into the cylinder of improperly atomized oil by a partially clogged or otherwise defective injection nozzle. This positioning of the plug relative to the combustion chamber and the direction of injection of the fuel provides substantial insurance against fouling or short-circuiting of the insulated portions of the plug due to unatomized liquid fuel or accumulations of carbonized fuel residue on the plug.

From the foregoing description it will be evident that the invention may be carried into effect with numerous different specific forms of apparatus, and that its application is not confined to any one particular engine construction. The invention is therefore to be considered as embracing all forms of apparatus falling within the scope of the appended claims when they are construed as broadly as is consistent with the state of the prior art.

While in order to assist the reader in an understanding of the invention we have set forth certain theories regarding the action which takes place in an engine structure embodying the invention, which theories are based upon observation of the performance of engines which we have

tested, it will be understood that reliance is not necessarily placed upon the correctness of such theories.

In our previously mentioned co-pending application Serial No. 747,134, certain forms of structure, not herein illustrated, for the conversion of specific kinds of gasoline engines to injection engines operating in accordance with the present invention, are claimed.

10 What we claim is:

1. A low compression internal combustion engine of the explosion type having liquid fuel injection commencing substantially ahead of top dead center and spark ignition for igniting a combustible air-fuel mixture formed prior to ignition, including a cylinder, a cylinder head, a piston in said cylinder having a substantially continuous upwardly extending collar portion, said piston, toward the end of the compression stroke, providing with the under side of the head a generally circular main combustion chamber substantially symmetrical with respect to the axis of the cylinder and having substantially minimum cylinder wall surface exposed and the major portion of said chamber being disposed within the piston, means for admitting air during the suction stroke in a manner creating whirling movement of the air about the axis of the cylinder during the suction stroke, which whirling movement continues during the compression stroke, including a valve located above the piston and opening toward the combustion chamber from the underside of said head, means for exhausting combustion gases including a valve located above the piston and opening toward the combustion chamber from the underside of said head, a spark plug projecting downwardly into said main combustion chamber and in a position exposed to the movement of the whirling air across the inner end of the plug during the suction and compression strokes, and fuel injection means for projecting finely divided liquid fuel during the latter portion of the compression stroke transversely of the cylinder into the portion of the combustion space formed by the piston so that a substantial portion of said combustible fuel-air mixture is formed in said portion of the combustion space below the level of the inner end of the plug.

50 2. A low compression internal combustion engine of the explosion type having liquid fuel injection commencing substantially ahead of top dead center and spark ignition for igniting a combustible air-fuel mixture formed prior to ignition, including a cylinder, a cylinder head, a piston in said cylinder having a substantially continuous upwardly extending collar portion, said piston, toward the end of the compression stroke, providing with the under side of the head a generally circular main combustion chamber substantially symmetrical with respect to the axis of the cylinder and having substantially minimum cylinder wall surface exposed and the major portion of said chamber being disposed within the piston, means for admitting air during the suction stroke in a manner creating whirling movement of the air about the axis of the cylinder during the suction stroke, which whirling movement continues during the compression stroke, including a valve located above the piston and opening toward the combustion chamber from the underside of said head, means for exhausting combustion gases including a valve located above the piston and opening toward the combustion chamber from the underside of said

head, a spark plug projecting downwardly into said main combustion chamber and in a position exposed to the movement of the whirling air across the inner end of the plug during the suction and compression strokes, and fuel injection means for projecting a plurality of jets of finely divided liquid fuel during the latter portion of the compression stroke transversely of the cylinder and in an obliquely downward direction into the portion of the combustion space formed by the piston so that a substantial portion of said combustible fuel air mixture is formed in said portion of the combustion space below the level of the inner end of the plug.

5 3. A low compression internal combustion engine of the explosion type having liquid fuel injection commencing substantially ahead of top dead center and spark ignition for igniting a combustible air-fuel mixture formed prior to ignition, including a cylinder, a cylinder head, a piston in said cylinder having a substantially continuous upwardly extending collar portion, said piston, toward the end of the compression stroke, providing with the under side of the head a generally circular main combustion chamber substantially symmetrical with respect to the axis of the cylinder and having substantially minimum cylinder wall surface exposed and the major portion of said chamber being disposed within the piston, means for admitting air during the suction stroke in a manner creating whirling movement of the air about the axis of the cylinder during the suction stroke, which whirling movement continues during the compression stroke, including a valve located above the piston and opening toward the combustion chamber from the underside of said head, means for exhausting combustion gases including a valve located above the piston and opening toward the combustion chamber from the underside of said head, a spark plug located in said head and projecting downwardly into said main combustion chamber and in a position exposed to the movement of the whirling air across the inner end of the plug during the suction and compression strokes, and a fuel injector located in said head for projecting finely divided liquid fuel during the latter portion of the compression stroke transversely of the cylinder into the portion of the combustion space formed by the piston so that a substantial portion of said combustible fuel-air mixture is formed in said portion of the combustion space below the level of the inner end of the plug.

4. A low compression internal combustion engine of the explosion type having liquid fuel injection commencing substantially ahead of top dead center and spark ignition for igniting a combustible air-fuel mixture formed prior to ignition, including a cylinder, a cylinder head, a piston in said cylinder having a substantially continuous upwardly extending collar portion, said piston, toward the end of the compression stroke, providing with the under side of the head a generally circular main combustion chamber substantially symmetrical with respect to the axis of the cylinder and having substantially minimum cylinder wall surface exposed and the major portion of said chamber being disposed within the piston, means for admitting air during the suction stroke in a manner creating whirling movement of the air about the axis of the cylinder during the suction stroke, which whirling movement continues during the compression stroke, including a valve located above the piston and opening toward the combustion chamber from the underside of said

and opening toward the combustion chamber from the underside of said head, means for exhausting combustion gases including a valve located above the piston and opening toward the combustion chamber from the underside of said head, a spark plug located in the head and projecting downwardly into said main combustion chamber to one side of a diameter of the cylinder and in a position exposed to the movement of the whirling air across the inner end of the plug during the suction and compression strokes, and fuel injection means located in said head on the opposite side of said diameter, said injection means having orifices for projecting dur-

ing the latter portion of the compression stroke a plurality of jets of finely divided liquid fuel transversely of the cylinder into the portion of the combustion space formed by said piston, at least one of said orifices being positioned so that the axial projection of the center line of the fuel jet formed thereby intersects the surface of said piston during the period of fuel injection on the same side of said diameter as that of the spark plug and below the level of the inner end of the spark plug. 5
